UNITED STATES PATENT OFFICE.

HENRY K. GILBERT, OF CHICAGO, ILLINOIS, ASSIGNOR TO AMERICAN BRAKE SHOE & FOUNDRY COMPANY, A CORPORATION OF NEW JERSEY.

BRAKE-SHOE AND METHOD OF MAKING SAME.

No. 838,316.

Specification of Letters Patent.

Patented Dec. 11, 1906.

Application filed December 19, 1905. Serial No. 292,420.

To all whom it may concern:

Be it known that I, HENRY K. GILBERT, a citizen of the United States, residing at Chicago, in the State of Illinois, have invented 5 a certain new and useful Improvement in Brake-Shoes and the Methods of Making the Same, of which the following is a specification.

The invention relates to brake shoes of the 10 type having a cast body portion and a back portion of malleable metal. The objects of the invention are; to provide an improved back for brake shoes of the above type which shall be of greater strength than those heretofore provided and having a better attaching 15 surface for the cast metal body portion, and further, to provide an improved method of making the shoes and their back portions whereby the steps in making are few, the necessary 20 machinery simple and the cost of production small. The article and the steps of making the same are illustrated in the accompanying drawings, in which—

Figure 1 is a perspective view of the tube 25 from which the back or blank is to be made;

Figure 2 is a perspective showing the slots cut in the ends of the tube, which operation constitutes the first step in the process;

Figure 3 is a perspective showing in full 30 lines the blank after the end portions of the tube have been flattened down leaving them somewhat corrugated, and in the dotted lines the outline of the body portion which is to be cast embracing the back portion or blank;

Figure 4 is a perspective showing one end 35 of a modified form of my blank, and

Figure 5 is a perspective illustrating another form of blank.

Figure 1 shows the tube from which the 40 back plate of the shoe is to be made and comprises a section from a square commercial tube. The first step in the process is the cutting of the slots 7, 7, at a sufficient distance apart to form the key-way lug 8. These lugs 45 are cut so as to sever all of the tube except

the bottom section or side 9. The next step is the cutting out of the top portions 10 on either side of the lug 8. This slot may be of greater or less width depending upon the desired width of the flat portion after the blank 50 is completed. The next step is the opening out of the side pieces 11 which leaves them in the corrugated shape shown in Figure 3.

The plate may also be curved longitudinally at the same time that it is being flattened. 55 The completed back plate is shown in full lines in Figure 3, while the cast portion is indicated by the dotted lines. It will be observed that the cast portion extends above and below the flat portions of the back plate, 60 and also up and over the lug 8, thereby reinforcing and strengthening such lug 8 and more effectually joining the back and body portions of the shoe. Figure 4 illustrates one of the modifications to which the invention 65 is subject. In this modification the central portion of the flat part is cut out to provide a better attaching surface for the cast metal. Figure 5 discloses another modification on the same order, the flat piece having been divided 70 and spread apart. These divided portions 12 may be made to pass through the body portion of the shoe at any desired angle. It will be understood that the invention is not confined to use with square tubes, although 75 this is my preferred form of blank. Round tubes or tubes of various other shapes might be used without departing from the invention. It is also apparent that the width of the slot 10 might be varied, and in fact a cut of only 80 the width of the cutting tool might be made instead of cutting out a section as illustrated. The corrugating of the flat portion of the back plate serves not only to stiffen the plate, but also provides a better attaching surface 85 for the cast metal. The provision of the cast metal over and around the lug 8 constitutes an important feature of my invention and gives a key-way lug of great strength. It will also be seen that the number of steps involved in the production of the back plate 90 are few and that the labor incident to the production of the blank from commercial stock is a minimum.

Having thus described my invention and 95 illustrated its use, what I claim as new, and desire to secure by Letters Patent, is the following:

1. The process of making brake shoe blanks which consists in making two cross slots 100 through a portion of a metal tube, cutting the tube longitudinally to its opposite ends from such cuts and flattening out that portion of the tube which is cut longitudinally.

2. The process of making brake shoe blanks 105 which consists in making two cross slots

through three sides of a rectangular metal tube, cutting the tube longitudinally in opposite directions from the cross slots on the side opposite the unsevered portion of the shoe 5 and flattening out that portion of the tube which is cut longitudinally.

3. The process of making brake shoe blanks which consists in making two cross slots through three sides of a rectangular metal 10 tube, cutting out longitudinal sections from the cross slots to the ends of the tube on the side opposite the unsevered side of the tube and flattening out that portion of the tube which is cut longitudinally.

15 4. The process of making brake shoe blanks which consists in making two cross slots through three sides of a rectangular metal tube cutting out longitudinal sections from the cross slots to the ends of the tube on the 20 side opposite the unsevered side of the tube, and flattening out and leaving corrugated

that portion of the tube which is cut longitudinally.

5. A brake shoe blank comprising a central tubular section and integral flat end sections 25 provided with corrugations.

6. A brake shoe blank of malleable metal comprising a central section shaped to receive a holding key, and extended end sections formed by flattening the end projections of 30 the central section.

7. A brake shoe blank comprising a tube with its central portion intact and its ends split and flattened to support the body of the 35 brake shoe.

In testimony whereof I have hereunto signed my name in the presence of the two subscribed witnesses.

HENRY K. GILBERT.
